UNITED STATES PATENT OFFICE.

NATHAN HERZOG, OF COLUMBUS, OHIO.

BOOT.

SPECIFICATION forming part of Letters Patent No. 511,141, dated December 19, 1893.

Application filed August 18, 1893. Serial No. 483,470. (No model.)

To all whom it may concern:

Be it known that I, NATHAN HERZOG, a citizen of the United States, residing at Columbus, in the county of Franklin and State of Ohio, have invented certain new and useful Improvements in Boots; and I do hereby declare the following to be a full, clear, and exact description of the invention, such as will enable others skilled in the art to which it applies to make and use the same.

The object of my invention is so to improve the ordinary leather boot that it shall be rendered impervious to water and warm and comfortable for use by men much exposed to wet or cold weather. In other words it is the object of my invention to provide a boot that shall embody all of the advantages of the clumsy and unsightly rubber water-proof boot heretofore in use and at the same time shall be neat and elegant in appearance so that it may be worn on the street or in the house just as is the ordinary unlined leather and non-water-proof boot.

The improvements claimed are set forth in the following specification.

In the accompanying drawings, Figure 1 is a vertical sectional view of the lower part of a boot made in accordance with my invention; and Fig. 2 is a sectional view taken transversely of the foot portion of the boot.

In the manufacture of a boot embodying my improvements, I take a boot-shaped foot covering 1 of felt or wool that is to constitute the lining of the boot and put it on a suitable last. I then take two pieces of water-proof material 2 and 3, preferably oiled cambric, of sufficient size and of proper shape to cover the leg about the ankle and the upper side of the foot. The lower or sole edge of the inner piece 2 of the oiled cambric is whip-stitched onto the sole of the felt lining 1. Over these stitches and covering the sole of the lining 1, I secure by whip stitches 4 the

insole 5. The usual boot top or upper of leather is then lasted onto the lining and a feather formed on the insole. The welt 6, the edge of the upper and the outer piece of cambric 3 are now secured to the bottom of the insole. The space on the insole within the welt is filled with shoemaker's wax and on this is placed a layer of tarred paper. The middle sole 7 is then placed on and upon this another layer of wax and tarred paper. The boot is now ready to receive the outsole 8 which is secured to the welt in the usual way.

In order that the boot top and linings shall not become distorted with respect to each other by the pulling on the boot straps, I form the boot straps of one continuous piece 9 which is passed down the sides of the boot 6 and under the heel portion of the insole.

A boot constructed in accordance with my invention will be impervious to water and at the same time warm and comfortable to the wearer. Externally it has the same neat and elegant appearance as the ordinary leather boot, is equally as durable, and may be worn upon the street without attracting attention.

What I claim, and desire to secure by Letters Patent, is—

A leather boot having an interior lining of felt or woolen cloth extending over the vamp and insole, that is, so as to cover the entire foot of the wearer, two intermediate layers of water-proof material secured in place on opposite sides of the insole by separate stitching, and the said insole having a covering of water-proof material, substantially as described.

In testimony whereof I affix my signature in presence of two witnesses.

NATHAN HERZOG.
